HANGER FOR GARMENTS

Rudolph Bernhardt, Chicago, Ill.

Application July 16, 1937, Serial No. 153,919

2 Claims. (Cl. 223—93)

This invention relates to hangers for supporting various garments but is intended particularly for light-weight dresses which are apt to slip off the ordinary garment hanger.

5 The objects of the invention are to provide a hanger for dresses and the like, which will be simple and cheap in construction and efficient in operation, and which will serve to secure or hold dresses or the like in position on the supporting bar; to provide an improved garment hanger having means for clamping the garment at either end of the supporting bar, which may be actuated by pressure on the clamping member at the center of the bar, said clamping member also coacting with the usual supporting members; to provide a device of the character set forth in which the clamping members constitute the ends of a leaf spring; and to provide such other advantages as will be described more fully hereinafter.

20 In the accompanying drawing illustrating this invention,

Figure 1 is a front view of my improved hanger showing the clamping members in engaged position and also showing them raised, in dotted lines;

Figure 2 is an enlarged detail sectional view of the central portion of the device; and

Figure 3 is a cross section taken on the line 3—3 of Figure 2.

30 The drawing illustrates the invention as applied to a hanger having a wooden supporting bar 5 of any suitable shape, although it may also be applied to other common forms of bars which may be formed of wire or the like. The supporting hook 6 has a shank or stem 7, the lower end of which engages with the hole 8 in the center of the bar. The stem has one or more lugs or projections 9 which are forced into the wood and serve to keep the hook in fixed position with respect to the bar.

45 The hook is further held in position by a bracket 10 which has a saddle portion 11 that fits closely over the bar and is provided with a hole 12 for the stem 7, as shown in Figure 2. The transverse portion of the saddle engages with the projections 9 to hold the stem in position. The saddle is secured to the bar by means of a pin or rivet 13 that passes through the sides of the saddle and of the bar and engages with the end of the stem, so that these parts are all held securely in assembled position.

50 The bracket 10 has outwardly and upwardly extending branches or arms 14 which are preferably made channel-shaped in cross section to

strengthen the same and which terminate in upwardly extending bearings 15.

The garment clamping means comprise a flat spring 16 having a hole 17 at the center to provide a bearing on the stem 8 which holds the spring against longitudinal movement but permits lateral movement of the central portion. The ends of the spring pass through holes or slots 18 in the bearings 15 and extend out to points adjacent to the ends of the bar 5. The ends are 10 provided with clamping members 19 preferably in the form of felt pads which are riveted or otherwise secured thereto.

The spring is curved or shaped so that the central support will cause the ends to press 15 against the ends of the bar.

When the hanger is to be used, the user presses down on the center portion of the spring which causes the ends to be raised as shown in dotted lines in Figure 1. The dress or other garment 20 such as indicated at 20 is then placed in position on the bar with the shoulders or shoulder straps located under the pads 19. The spring or clamping member is then released, which permits the pads to press against the shoulder portions which 25 hold the garment securely in position. It will also be noted that other garments of various kinds may be hung and clamped in position on the hanger, so that they will not be apt to become disengaged therefrom as in the other form 30 of hangers.

While I have shown and described a perfected embodiment of my invention, it will be noted that changes may be made in the details of construction or arrangement of parts in order to adapt 35 the same to different forms of hangers, and therefore I do not wish to be limited to the particular construction shown except as specified in the following claims, in which I claim:

1. The combination with a garment hanger 40 having a bar and supporting hook, of a spring extending longitudinally of the bar and having a hole for engagement with the hook, a bracket secured to the bar, and having upwardly extending bearings for the spring said bearings being 45 spaced apart a sufficient distance so that pressure on the intermediate portion of the spring will raise the outer ends thereof for inserting and releasing garments and also being sufficiently close to the hook to leave the outer ends of the bar 50 free for receiving the garments, the spring being sufficiently strong and bent so that the ends thereof are urged toward the bar with sufficient pressure to hold the garment on the bar.

2. In a hanger, the combination of a bar, a 55

supporting hook having a shank engaging with a hole in the bar and having projections also engaging with the walls of the hole, a bracket having a saddle fitting over the bar with a hole for receiving the shank, said bracket engaging with the projections, a pin engaging with the saddle and bar at the lower end of the shank for holding the parts together, bearings extending upwardly at the ends of the bracket, a leaf spring engaging with said bearings and extending longitudinally of the bar and having a hole for engagement

with the shank, whereby the spring is held against longitudinal movement while permitting transverse movement of the central portion thereof, said spring being sufficiently stiff and formed so that the ends are pressed toward the bar with proper tension to hold the garments on the bar, and means at the ends of the spring for engagement with the garment to hold the same upon the bar. 5

RUDOLPH BERNHARDT. 10
